UNITED STATES PATENT OFFICE.

ALBERT C. BARLEY, OF STREATOR, ILLINOIS.

DESIGN FOR A COMBINED AUTOMOBILE BODY, HOOD, AND RADIATOR.

53,652.

Specification for Design.

Patented July 29, 1919.

Application filed October 31, 1916. Serial No. 128,796. Term of patent 7 years.

To all whom it may concern:

Be it known that I, ALBERT C. BARLEY, a citizen of the United States, residing at Streator, in the county of La Salle and State of Illinois, have invented a new, original, and ornamental Design for a Combined Automobile Body, Hood, and Radiator, of which the following is a specification, reference being had to the accompanying drawing, forming part thereof.

Figure 1 is a side elevation, and Fig. 2 is a front elevation of the body, showing my new design.

I claim:

The ornamental design for a combined automobile body, hood, and radiator as shown.

ALBERT C. BARLEY.
